United States Patent Office

Des. 208,872
Patented Oct. 10, 1967

208,872

CUP

Paul Davis, Beverly, Mass., assignor to Sweetheart
Plastics, Inc., Wilmington, Mass., a corporation of Maryland

Filed May 23, 1966, Ser. No. 2,402

Term of patent 14 years

(Cl. D44—9)

FIG. 1

FIG. 2

FIG. 3

FIG. 4

FIG. 5

FIG. 6

FIG. 1 is an elevational view, partly in section, of a cup showing my new design;

FIG. 2 is a bottom plan view thereof;

FIG. 3 is an elevational view, partly in section, of a cup showing another form of my new design;

FIG. 4 is a bottom plan view thereof;

FIG. 5 is an elevational view, partly in section, of a cup showing another form of my new design; and

FIG. 6 is a bottom plan view thereof.

I claim:

The ornamental design for a cup, as shown and described.
